UNITED STATES PATENT OFFICE.

WILLIE G. EATON, OF NASHUA, NEW HAMPSHIRE, ASSIGNOR TO THE DRAPER COMPANY, OF PORTLAND, MAINE, AND HOPEDALE, MASSACHUSETTS.

LOOM.

SPECIFICATION forming part of Letters Patent No. 623,951, dated April 25, 1899.

Application filed November 21, 1898. Serial No. 696,980. (No model.)

To all whom it may concern:

Be it known that I, WILLIE G. EATON, of Nashua, county of Hillsborough, State of New Hampshire, have invented an Improvement 5 in Looms, of which the following description, in connection with the accompanying drawings, is a specification, like letters and figures on the drawings representing like parts.

This invention relates particularly to looms 10 provided with mechanism for automatically supplying the shuttle with fresh filling; and my invention has for one of its objects the production of novel means for effecting a change of filling prior to the complete exhaustion of 15 the filling then in the shuttle.

Another object of my invention is to provide means for severing the thread from the filling-carrier ejected from the shuttle by the incoming fresh supply.

Various other novel features of construction and arrangement comprised in my invention 20 will be hereinafter described, and particularly pointed out in the claims.

I have herein illustrated the filling-supplying mechanism substantially as shown in 25 United States Patent No. 529,940, dated November 27, 1894, the operation of said mechanism being prevented when the shuttle is improperly boxed by or through the action of 30 a shuttle feeler or detector, substantially as shown in United States Patent No. 568,455, dated September 29, 1896.

Figure 1 is a partial left-hand side view of 35 a loom with one embodiment of my invention applied thereto, the lay being shown in its rearmost position. Fig. 2 is an enlarged top or plan view of the mechanism at the left-hand side of the loom as shown in Fig. 1, with the corresponding shuttle-box, a shuttle there- 40 in, and a feeler arranged to coöperate with the filling in the shuttle. Fig. 2^a is a detached view of the actuator forming a part of the controlling means for the filling-supplying mechanism to be described. Fig. 3 is a cross- 45 sectional view of the loom looking toward the inner end of the filling-supplying mechanism located at the right-hand side of the loom; and Fig. 4 is a similar view, but with the lay forward, showing the feed-severing means in 50 operative position.

The shuttle-box at the end of the lay adja- 55 cent the filling-supplying mechanism is cut away to permit the passage therethrough of the ejected filling-carrier from the shuttle, and the filling-feeler F, Figs. 3 and 4, mounted on the breast-beam A¹⁰, is and may be substantially as shown in said Patent No. 529,940. The shuttle-feeler k², fulcrumed at k³ on a fixed arm k⁴, the stud f, on which is mounted the usual transfeerer, (not shown,) the hub, 60 having arms c¹ c², rotatably mounted on the stud, the link e, connecting the arm c² and the upper end of the shuttle-feeler, the rock- shaft d¹, adapted to be rocked by or through the weft-fork in the absence of the filling, 65 the spring-controlled arm d², fast on said rock-shaft, and the link d⁴, longitudinally slotted at its upper end to receive a pin c⁵ on the arm c¹, are illustrated substantially as shown in Patent No. 568,455 and operate in a similar 70 manner.

The thread-severing means herein comprises a fixed and a movable cutting-blade, both mounted on the lower end of the shuttle-feeler k², the cutting edge of the fixed 75 blade c³⁰ being located slightly above the path of the filling-thread when the shuttle is properly boxed, as shown in Fig. 4. The movable cutting-blade c³¹ is pivoted at c³² on the feeler, the thread to be severed being caught between the opposed edges of the blades at the proper time, the movable blade having, as herein shown, an upturned tail c³³, limited as to its angular movement by stops 3 4, as clearly shown in Figs. 3 and 4, the upper end 85 of the tail being located in the path of some portion of the lay A³, such as the hand-rail R, so that when the shuttle is properly boxed and the shuttle-feeler is in the position shown in Fig. 4 the severing means will be operated 90 as the lay beats up.

It will be understood that the shuttle-feeler has a detecting movement only when a fresh supply of filling is to be inserted in the shuttle, as in Patent No. 568,455, referred to, so 95 that the cutting-blades will be operated only at such time, provided the shuttle is in the shuttle-box B¹⁰, to sever the thread of the ejected filling-carrier. The movable blade c³¹ is returned to normal open position by the 100

engagement of the tail c^{33} with a spring-finger s^{30} , shown as attached to the arm k^X , when the said tail is released by the operating portion of the lay. When the feeler on its detecting movement encounters and is stopped by the improperly-boxed shuttle, the slotted portion of the link d^4 permits such stoppage even though the arm d^2 of the rock-shaft d' may be in the position shown in Fig. 4, such 10 stoppage of the feeler preventing the operation of the filling-supplying mechanism in usual manner.

Referring now to Figs. 1 and 2, I have shown the front plate B^{15} of the shuttle-box B^{12} at 15 the opposite or left-hand end of the lay provided with bearings b^{15} for a rock-shaft b^{16} , having rigidly attached thereto the filling-feeler b^{17} , shown as an upturned and rearwardly-curved finger extending over the shuttle-box and adapted when depressed to engage the filling on the filling-carrier F' in the shuttle when the latter is properly boxed. By mounting the feeler on the front plate of the shuttle-box the feeler is positioned properly 20 relatively to the shuttle when the position of the plate is changed, such change being made as the shuttle wears. Were the feeler mounted on the lay, it would be stationary relative to the shuttle, the position 25 of which might be varied. A spring s^{10} , fixed at one end and at its other end attached to the rock-shaft b^{16} , normally maintains the feeler elevated above the path of the shuttle, a suitable stop b^{18} limiting the movement of 30 the rock-shaft due to the spring. The inner end of the feeler rock-shaft is provided with two branches $b^{19} b^{20}$, Fig. 1, located substantially one above the other and slightly flared or bent oppositely at their free ends, 35 while a dog b^{21} , fast on the rock-shaft, is herein shown as provided at its extremity with a roll b^{22} , the branches and dog extending toward the breast-beam. The bearing a^{30} 40 on the latter supports an upturned rocking plate or bunter a^{31} in the path of the roll b^{22} and normally maintained elevated by a spring s^{15} , stiffer than the feeler-spring s^{10} , so that as the lay comes forward the roll will engage and travel upward upon the bunter, rocking the 45 shaft b^{16} in the direction of the arrow 6 to depress the feeler. The amount of filling on the filling-carrier F' determines the extent of such movement of the feeler, and when the feeler is stopped by engagement with the filling the 50 bunter a^{31} will yield more or less as the lay completes its forward movement.

The usual shipper-handle 39, Fig. 2, moves in the notched plate a^{39} . At b^4 is pivoted a knock-off lever b^5 , normally resting against or 55 adjacent the shipper-handle, the free end of the lever being acted upon by the weft-fork mechanism when it is desired to release the shipper-handle, and thereby through usual means stop the loom.

65 The weft-fork mechanism herein illustrated is substantially that shown in United States Patent No. 529,943, comprising a stand b^7 ,

mounted on the breast-beam and provided with a guideway in which a slide b^9 is adapted to reciprocate, the weft-fork b^{12} , pivoted at b^{16} 70 on the slide, having a rearwardly-projecting tail b^{13} to be engaged by a hook b^{14} , pivoted on the upper end of the weft-hammer A^{19} when the filling is absent as the lay beats up.

A latch d^5 is pivoted at d^4 on the slide b^9 and 75 has on its under side a cam 12, the free down-turned end of the latch being adapted to at times operate the knock-off lever b^5 , a wedge d^6 , longitudinally movable in the slide b^9 , having a cam 14 on its upper side to coöperate 80 with the latch-cam 12, the outer edge of the wedge being downturned, as at 44, to meet a shoulder 45 under certain conditions, said shoulder forming a part of the stand b^7 , all substantially as in said Patent No. 529,943. 85 On the outer side of the stand b^7 I have mounted a sliding actuator m , (shown separately in Fig. 2^a), longitudinally slotted at m^1 to receive retaining-screws m^2 , extended into the stand, the rear end of the said actuator having 90 a lateral lug or projection m^3 , adapted to be engaged by a hook m^4 , pivoted at m^5 on an ear A^{20} on the weft-hammer, said ear being offset to clear the stand and the actuator. The outer end m^6 of the hook is T-shaped and 95 is acted upon by a leaf-spring s^{35} on the ear A^{20} to frictionally retain the hook in operative or inoperative position until positively moved therefrom. The hook is provided with a laterally-extended pin or stud m^7 , herein 100 shown as near its head end and in the path of movement of one or other of the branches $b^{19} b^{20}$ of the feeler rock-shaft b^{16} . At each forward beat of the lay the upper branch b^{19} will slide over or above the pin m^7 to thereby 105 maintain the hook m^4 inoperative. When, however, the filling in the shuttle has been exhausted sufficiently to permit a greater movement of the feeler into the shuttle, the branch b^{20} will be raised sufficiently to pass 110 beneath and lift the pin m^7 as the lay beats up to thereby depress the rear end of the hook to engage the lug or projection m^3 of the actuator m , so that the latter will be moved outward by the weft-hammer. The 115 outer end of the slide will at such time engage an upturned arm d^{20} , fast on the rock-shaft d' , turning the latter sufficiently to operate the filling-supplying mechanism in well-known manner to thereby insert a fresh 120 supply of filling into the shuttle before complete exhaustion of the filling then in the shuttle. When the shuttle, with its fresh supply of filling, thereafter enters the shuttle-box b^{12} , the feeling movement of the feeler will 125 be suspended and the rock-shaft b^{16} will be so positioned angularly as to cause the branch b^{19} to engage the pin m^7 and depress it to move the hook m^4 into inoperative position. It will thus be seen that the controlling means 130 for the filling-supplying mechanism is actuated by or through the weft-hammer in a positive manner and that the coöperation of said controlling means and weft-hammer is

governed by or through the feeler and effected upon exhaustion of the filling in the shuttle to a predetermined extent, the feeler being adjusted angularly with relation to the branch 5 b^{20} to bring the latter into operative position only when a small and predetermined amount of filling is left upon the filling-carrier.

The controlling means for the filling-supplying mechanism includes the rock-shaft d' , the actuator m , and the usual connections 10 between the rock-shaft d' and transerrer, as Patent No. 529,940, referred to, and the feeler-controlled rock-shaft b^{16} , with its branches b^{19} b^{20} , may be termed a "governing" device for 15 said controlling means. Should the filling fail, then the usual weft-fork mechanism will operate, and upon the first outward movement of the slide b^9 the end 44 of the wedge d^6 will engage the shoulder 45 to permit the 20 latch d^5 to drop on the knock-off lever, as in Patent No. 520,943, and at the second outward movement of the slide the latch, then behind the knock-off lever, will push the latter to release the shipper-handle and stop 25 the loom. An arm d^{30} is loosely mounted on the rock-shaft d' and is held by a spring S^X against the outer end of the slide b^9 , the spring pushing the slide inward, a depending extension d^{32} on the arm engaging the usual actuating-pawl of the take-up mechanism when 30 the arm d^{30} is rocked by the outward movement of the slide, so that the take-up will not be actuated at either the first or second movement of the said slide.

35 My invention is not restricted to the construction and arrangement herein shown, as the same may be modified or rearranged without departing from the spirit and scope of my invention. Neither is my invention 40 restricted to the use of the weft-fork mechanism herein shown.

Having described my invention, what I claim as new, and desire to secure by Letters Patent, is—

45 1. In a loom, a shuttle containing a supply of filling, filling-supplying mechanism, the weft-hammer, controlling means for said mechanism including a sliding actuator, a filling-feeler, a normally-inoperative connection between the weft-hammer and the actuator, and 50 a governing device for said connection, operative by or through the feeler upon exhaustion of the filling in the shuttle to a predetermined extent, to move said connection into operative position and thereby effect movement of the actuator by the weft-hammer and thereby actuate the controlling means.

55 2. In a loom, a shuttle containing a supply of filling, filling-supplying mechanism, the weft-hammer, controlling means for said mechanism including a sliding actuator, a co-operating hook mounted upon the weft-hammer, a filling-feeler, and a governing device for the hook, operative by or through the feeler upon 60 exhaustion of the filling in the shuttle, to move the hook into engagement with the actuator.

3. In a loom, filling-supplying mechanism, controlling means therefor, including a sliding actuator, the weft-hammer, a hook carried thereby, a governing device mounted on the lay, to move the hook into or out of position to engage the actuator, and a filling-feeler connected with and to operate said governing device to effect engagement of the hook 70 and actuator upon exhaustion of the filling in the shuttle to a predetermined extent.

4. In a loom, the lay, a spring-controlled filling-feeler mounted thereupon, a dog connected with the feeler, a yielding bunter to 80 engage the dog and move the feeler into engagement with the filling as the lay beats up, filling-supplying mechanism, controlling means therefor, including an actuator, an operating-hook for the actuator, and a governing device controlled by the feeler, to maintain the hook inoperative until exhaustion of 85 the filling in the shuttle to a predetermined extent.

5. In a loom, the lay, a filling-feeler mounted 90 thereon, a spring to retain the feeler inoperative, means to move the feeler positively to contact with the filling in the shuttle as the lay beats up, filling-supplying mechanism, controlling means therefor actuated by the weft-hammer, the weft-hammer, and a governing device operated by or through the feeler before the filling is exhausted in the shuttle, to effect the actuation of the controlling means.

6. In a loom, the lay having a shuttle-box, 100 a shuttle containing a supply of filling, filling-supplying mechanism, controlling means for said mechanism, a filling-feeler mounted on the front plate of the shuttle-box, and a governing device operatively positioned by 105 the feeler upon exhaustion of the filling in the shuttle to a predetermined extent, to effect the actuation of the controlling means.

7. In a loom, the lay having a shuttle-box, 110 a shuttle containing a supply of filling, filling-supplying mechanism, a filling-feeler mounted on the front plate of the shuttle-box, and means controlled by the feeler to effect operation of the filling-supplying mechanism upon exhaustion of the filling in the shuttle 115 to a predetermined extent.

8. In a loom, filling-supplying mechanism, controlling means therefor, including a rock-shaft having an arm fast upon it, and a sliding actuator to engage said arm and rock the 120 shaft, a weft-hammer, a hook carried thereby to slide the actuator, a filling-feeler, and means governed by said feeler to effect engagement of said hook and actuator before the complete exhaustion of the filling in the 125 shuttle.

9. In a loom, filling-supplying mechanism, controlling means therefor, including a rock-shaft and a sliding actuator to rock it, a weft-hammer, a filling-feeler, and means governed 130 thereby to effect the movement of the actuator by the weft-hammer upon exhaustion of the filling in the shuttle to a predetermined extent, combined with a shuttle-feeler, filling-

- severing means carried thereby, to sever the thread of the ejected filling-carrier, and operating connections between the rock-shaft and the shuttle-feeler.
- 5 10. In a loom, a shuttle containing a supply of filling, a shuttle-feeler, filling-severing means carried thereby, filling-supplying mechanism, controlling means therefor operative when the shuttle is properly boxed, a 10 filling-feeler to effect the operation of said controlling means upon exhaustion of the filling in the shuttle to a predetermined extent, and an actuating device for said filling-severing means, operative upon change of 15 filling to sever the thread of the ejected filling-carrier.
11. In a loom, the lay, filling-supplying mechanism, a shuttle-feeler operatively connected therewith, filling-severing means 20 mounted on the shuttle-feeler, and an operating device for said means, operative upon change of filling to sever the thread of the ejected filling-carrier.
12. In a loom, the lay, filling-supplying 25 mechanism, means mounted independent of the lay to sever the thread of the ejected filling-carrier upon change of filling, and means to actuate said severing means.
13. In a loom, the lay, filling-supplying 30 mechanism, a depending arm fulcrumed above the path of the lay, filling-severing means mounted thereupon, upon the arm, an actuating device for said means, and means to position the arm, both operative upon 35 change of filling, to effect severance of the thread of the ejected filling-carrier.
14. In a loom, the lay, filling-supplying mechanism, means to sever the thread of the ejected filling-carrier upon change of filling, and an actuator for said means, carried by 40 the lay wholly above the warp.
15. In a loom, the lay, filling-supplying mechanism, a shuttle-feeler operatively connected therewith, filling-severing means 45 mounted on the shuttle-feeler, and comprising a fixed and a movable blade to engage between them the thread of an ejected filling-carrier, and a device mounted on the lay to actuate the movable blade upon change of filling.
16. In a loom, the lay, filling-supplying mechanism, a shuttle-feeler operatively connected therewith, filling-severing means 50 mounted on the shuttle-feeler, and comprising a fixed and a movable blade to engage between them the thread of an ejected filling-carrier, and a device mounted on the lay to actuate the movable blade upon change of filling, and means to return the said blade to inoperative position.
- 55 In testimony whereof I have signed my name to this specification in the presence of two subscribing witnesses.

WILLIE G. EATON.
